[57] CLAIM

The ornamental design for a book page holder, substantially as shown and described.

DESCRIPTION

FIG. 1 is a perspective view of a book page holder showing my new design;

FIG. 2 is a top plan view;

FIG. 3 is a front elevational view;

FIG. 4 is a bottom plan view; and

FIG. 5 is a cross-sectional view taken along line 5—5 of FIG. 3.

*Fig. 1.**Fig. 2.**Fig. 3. → 5.**Fig. 4. → 5.**Fig. 5.*
